UNITED STATES PATENT OFFICE.

GEORGE HERKEN AND HARVEY L. HERKEN, OF LA CROSSE, WISCONSIN.

PARCEL-POST MAILING CASE.

Application filed September 28, 1925. Serial No. 59,126.

This invention relates to a receptacle intended to hold clothes to be sent to the laundry and returned in the same receptacle. One object of the invention is to so construct the cover of the receptacle that an address card may be associated therewith for display through a sight opening and securely but releasably held in place.

Another object of the invention is to so mount the address card that there will be no danger of its accidentally slipping out of place but at the same time permit of its being easily removed when it is desired to reverse it so that the address upon its other face will be displayed through the sight opening.

This invention is illustrated in the accompanying drawing, wherein—

Figure 1 is a view showing the improved receptacle or case in side elevation;

Fig. 2 is a longitudinal sectional view through the case taken on the line 2—2 of Fig. 1;

Fig. 3 is a transverse sectional view through the case taken on the line 3—3 of Fig. 1, and

Fig. 4 is an enlarged view of the address card looking at one face thereof.

The case forming the subject-matter of this invention is in the form of a box which includes a receptacle or body portion 1 and a cover 2. The box is preferably oblong, but it will be understood that it may be of any shape desired. In the present illustration, the cover telescopes onto the receptacle and is secured by straps 3 which extend about the receptacle and are fastened, as shown in Fig. 1. A handle 4 has also been provided so that the case may be easily carried from one place to another. A sight opening 5 is formed in the cover 2 and is closed by a transparent sheet 6 held against the inner face of the cover by a backing sheet 7 which may be formed of the same kind of material from which the cover is made or of any other suitable material and is disposed in covering relation to the sight opening and transparent sheet 6 and secured by fasteners 8 which extend through the backing sheet and cover and also through spacing strips 9 disposed along the sides of the sight opening and across one end thereof. It will, therefore, be seen that the backing sheet together with the strips 9 form a pocket of slightly greater length and width than the sight opening and open at one end so that

the address card 10 may be passed into the pocket through its open end. The address card is somewhat longer than the pocket and has one end portion extending out of the pocket when the card is in place, this extended end portion being formed with an opening 11 to receive a snap fastener stud 12 which projects inwardly from the top wall of the cover, as shown in Fig. 2. It will be readily understood that, when the stud 12 is disposed in the opening 11, the address card will be prevented from having longitudinal movement and, therefore, cannot slip out of the pocket. In order to prevent danger of the address card slipping out of engagement with the stud, there has been provided a tab 13 which is secured to the backing sheet 7 by means of a fastener 14 and carries a snap socket 15 to be snapped into engagement with the stud 12.

When this receptacle is in use, the clothes to be washed are packed in the body or receptacle 1 of the case and the address card put in place with its face exposed through the sight opening having the name of the sender after the "From" mark shown in Fig. 4 and the name of the laundry to which the package is to be sent after the "To" mark. The socket 15 is snapped into engagement with the stud and since the stud extends through the opening 11 of the address card there will be no danger of the card slipping out of the pocket when the receptacle is sent through the mail. If the address card slips out of place, it is necessary for the postal inspectors to open the package and replace the card. This requires the time and services of the postal employees and also causes delay. After the clothes have been laundered, they are replaced in the original package and the employee in the shipping department of the laundry releases the tab from engagement with the stud and after withdrawing the address card from the pocket reverses it and replaces it with the opposite face of the card exposed through the sight opening. This face of the card has the name of the laundry after the "From" mark and the name of the person to whom the laundry is to be sent after the "To" mark. It will, therefore, be seen that the same address card may be used a great many times and that when in place it will be securely held and prevented from accidentally slipping out of the pocket. While it is stated that the case is to be used for

sending clothes to a laundry and for returning them, it will be understood that other articles could be packed in the receptacle and also that any receptacle having a cover or wall formed with a sight opening could have the improved address card holding means associated with its sight opening.

Having thus described the invention, we claim:

- 10 1. In combination with a receptacle having a wall formed with a sight opening, a backing sheet disposed in covering relation to said sight opening and overlapping the inner face of said wall along the sides and one end of the sight opening, spacing strips between the inner face of said wall and the said overlapping portions of said backing sheet and together with the backing sheet forming a pocket open at one end, a fastener element carried by said receptacle in spaced relation to the open end of said pocket, an address card removably fitted into said pocket for display through said sight opening and of greater length than the backing sheet to provide an end portion projecting from the open end of the pocket, the extended end portion of said card being formed with an opening to receive said fastener, and a tab extending from said back-

ing sheet at the open end of the pocket and releasably engaged with said fastener to retain said card in engagement with the fastener.

2. In combination with a receptacle having a wall formed with a sight opening, spacing strips secured to the inner face of said wall along the sides and one end of said sight opening, a backing sheet disposed in covering relation to said sight opening and secured against said strips and forming a pocket open at one end, a fastener stud extending from the inner face of said wall in spaced relation to the open end of said pocket, an address card of greater length than said backing strip passed into said pocket through the open end thereof and having one end portion extended outwardly and formed with an opening to receive said stud, and a tab extending from said backing sheet, and a socket carried by said tab and adapted to be releasably engaged with said stud to retain said tab and card in engagement with the stud.

In testimony whereof we affix our signatures.

GEORGE HERKEN. [L. S.]
HARVEY L. HERKEN. [L. S.]
